UNITED STATES PATENT OFFICE.

GEORGE ROBINSON AND JAMES ROBINSON, OF LONDON, ENGLAND.

TENNIS AND LIKE RACKET.

Application filed March 22, 1928, Serial No. 263,882, and in Great Britain April 2, 1927.

This invention relates to improvements in tennis and like rackets.

In tennis and similar rackets as at present constructed two lengths of gut or other material forming the mesh are employed, one length being used for the horizontal and one for the transverse members thereof.

This invention consists in stringing or forming the mesh of the racket so that each string or member or pair of strings or members of the mesh is separate from adjacent strings or pairs of strings whereby if a string breaks or becomes worn the string or pair of strings can be readily replaced without adjacent strings becoming slackened or affected in any way.

The invention will be described with reference to the accompanying drawings:—

Fig. 1 is a vertical section through a tennis racket having the strings forming the mesh arranged in pairs, each pair being separate from adjacent pairs of strings.

Fig. 2. Side view of the tennis racket shown in Fig. 1.

Fig. 3. is an enlarged side view of a part of the frame showing the holes and grooves formed therein to receive the strings.

Fig. 4. is a similar enlarged side view showing the strings in position.

Fig. 5. is a section on line 5—5 Fig. 4.

Fig. 6. is a diagrammatic view of a length of gut forming a pair of strings showing the manner in which the ends of the strings are held.

Fig. 7. is an enlarged side view of a part of the frame of a racket in which each string is separate from adjacent strings, showing the arrangement of holes and grooves to receive the string.

Fig. 8. is a diagrammatic view of a single string showing the manner in which the end of the string is held.

Fig. 9. is an enlarged view of a part of the frame of a racket near the handle showing the holes for receiving the end of a longitudinal string.

Fig. 10. is a similar view showing the end of the string in position.

Fig. 11. is a diagrammatic view of a pair of longitudinal strings formed from a single length showing the manner in which the ends are held.

As applied to a racket A in which the strings B are arranged in pairs (see Figs. 1 to 6) one side of the frame is formed with four holes a^1 , a^2 , a^3 , a^4 for each pair of

strings, connected together by grooves c^1 , c^2 , c^3 , c^4 arranged as shown in Fig. 3 whilst the other side of the frame is formed with two holes a^5 , a^6 , connected together by the groove c^5 .

The gut forming the strings B is cut into lengths equal to the length of a pair of strings and one end b^1 is threaded through the hole a^1 from the inside of the frame to the outside of the frame as indicated by the arrows in Figs. 5 and 6, it is then threaded in the opposite direction through the hole a^2 and back to the outside of the frame through the hole a^3 . The free end b^1 is then passed under the portion of the string b^2 in the groove c^1 connecting the holes a^1 and a^2 so that when the string is pulled taut, the portion b^2 will grip the end part b^1 lying in the groove c^2 between it and the frame.

The other end b^3 of the string B is then threaded across the frame, through the hole a^5 along the groove c^5 back through the hole a^6 and again across the frame to the hole a^4 to the outside of the frame. It is then threaded through the hole a^3 to the inside of the frame, back up through the hole a^2 and the end passed under portion b^4 of the string lying in the groove c^3 connecting the holes a^4 , and a^5 . When the end is pulled taut the portion b^4 of the string grips the end portion b^3 lying in the groove c^4 between it and the frame so that the whole string is firmly held in a taut condition.

Each series of holes a^1 , a^2 , a^3 , a^4 may be arranged at one side of the frame and each pair of holes a^5 and a^6 at the other side but it is preferred to arrange a^1 , a^2 , a^3 , a^4 and the holes a^5 , a^6 alternately so that the fastening of one pair of strings is at one side of the frame and the fastening of the next pair of strings is at the opposite side of the frame.

As applied to a racket having single strings each separate from one another (Figs. 7 and 8) three holes a^1 , a^2 , a^3 are formed at each side of the frame for each string B¹. The holes a^1 and a^2 being connected by the groove c^1 and a second groove c^2 terminating at the hole a^3 being arranged transversely to the groove c^1 . The end b^1 of the string B is threaded from the inside of the frame through the hole a^1 along the groove c^1 to the hole a^2 . It is then threaded in the opposite direction through the hole a^2 to the inside of the frame and back through the hole a^3 to the outside of the frame. The end b^1 is then passed under the portion b^2 of the

string, being in the groove c^1 connecting the holes a^1 and a^2 so that when the string is pulled taut the portion b^2 will grip the end portion b^1 lying in the groove c^2 between it and the frame.

5 The other end of the string is held in position in exactly the same way.

To hold the longitudinal strings near the longitudinal central line of the racket four holes are formed through the wedge of the racket the holes d^1 and d^4 being oblique and the holes d^3 and d^2 being transverse. One end b^1 of the string B is passed through the oblique hole d^1 from the inside of the 10 wedge, through the transverse holes d^2 back through the transverse hole d^3 and passed under the portion b^2 of the string between the holes d^1 , d^2 so that this portion b^2 of the string between the holes d^1 , d^2 grips the end 15 portion b^1 when the string is pulled taut.

The other end b^3 of the string is passed to the head of the racket and threaded through the holes a^5 , a^6 passed obliquely through the hole d^4 through the transverse hole d^2 back 20 through the transverse hole d^3 , and passed under the portion b^4 of the string between the holes d^2 and d^4 so that this portion b^4 25 grips the end portion b^3 when the string is pulled taut.

30 A racket string as above described has each individual string or pair of strings separate from adjacent strings or pairs of

strings, and it is a simple matter to insert a new string should one break or become worn.

What we claim as our invention and desire to protect by Letters Patent is:—

1. A tennis or like racket comprising a frame a plurality of separate strings forming the mesh, groups of holes in the frame through which each end of each string is threaded in and out, the end being ultimately passed under a portion of the string lying between two holes so that when the string is pulled taut it will be gripped and held by this portion without the use of wedges. 40

2. A tennis or like racket comprising a frame, a plurality of separate strings forming the mesh, groups of holes in the frame through which each end of each string is threaded in and out, grooves connecting adjacent holes in each group in which the string lies so as not to extend above the surface of the frame the end of each string being ultimately passed under a portion of the string lying between two holes so that when the string is pulled taut it will be gripped and held by this portion without the use of wedges. 50

55 In testimony whereof we have hereunto set our hands.

60
GEORGE ROBINSON.
JAMES ROBINSON.
